US0D1027077S

(12) **United States Design Patent** (10) **Patent No.:** **US D1,027,077 S**
(45) **Date of Patent:** **** May 14, 2024**

(54) **EXERCISE EQUIPMENT**

(71) Applicant: **Jianguang Zhang**, Los Angeles, CA
(US)

(72) Inventor: **Jianguang Zhang**, Los Angeles, CA
(US)

(**) Term: **15 Years**

(21) Appl. No.: **29/745,182**

(22) Filed: **Aug. 4, 2020**

(51) LOC (14) Cl. **21-02**

(52) U.S. Cl.

USPC **D21/681**

(58) **Field of Classification Search**
